Claims priority, application Italy, Nov. 3, 1961,
19,789/61

9 Claims. (Cl. 260—941)

This invention is directed to a new class of compounds of the following general formula (1):

in which R, R₁ and R₂ represent the same or different alkyl radicals of low molecular weight, having linear or branched chains, saturated or unsaturated, at least one of the R, R₁, R₂ radicals containing one or more fluorine atoms; and R₃ is hydrogen or a phenyl radical, and X stands for oxygen or sulfur. R and R₁ stand preferably for CH₃, C₂H₅F, C₂H₅, R₂ is preferably a radical selected from the group consisting of CH₃, C₂H₅, CH₂CF₂CHF₂, C(CH₃)₂C≡CH and C₂H₄F.

Another object of the present invention is to provide a new process for preparing the compounds of the formula (1). Said process consists in reacting the alkaline

2

salts of the O,O-dialkylthio- or dithiophosphoric acids with haloacetic esters, according to the following scheme:

wherein R, R₁, R₂, R₃ have the above indicated meaning, Me is an alkali metal, and Hal is chlorine or bromine. The new compounds occur as oily substances which are insoluble in water and soluble in organic solvents. They are characterized by a high activity against parasites, particularly against mites. It is known that it is particularly desirable that substances employed for control of mites display an effective action either against adults or against the eggs, and moreover that they be endowed with great persistence of activity, namely that they maintain their efficiency for a long time after application.

It has surprisingly been found that the compounds belonging to the class which is the object of the present invention possess said requirements, and some of them to a far greater extent than the products usually employed for control of this type of phytophagous pest.

In this connection, comparison data is reported below, comparing the action of a number of said new compounds toward *Metatetranychus ulmi* with several products commonly employed as acaricides.

Product	Active substance (AS) concentr. %	Percent mortality of adults by direct spraying	Eggs—Percentages of unhatched eggs	
			Direct spraying	Residual effect
$\begin{array}{c} \text{C}_2\text{H}_5\text{O} \\ \\ \text{P}=\text{S}-\text{CH}-\text{COO}-\text{CH}_2-\text{CH}_2\text{F} \\ \\ \text{C}_2\text{H}_5\text{O} \quad \text{S} \quad \text{C}_6\text{H}_5 \end{array}$	0.01 0.1	27 100	2 100	94 100

NOTE: Spraying was carried out on discs of apple tree leaves.

Ovicidal effect was determined on eggs laid by untreated females on treated discs, while removing the mites after 24 hours (see Example 21).

No residual effect is noted for the product "Fac" having highest activity against the adults, although it possesses also a remarkable ovicidal action upon direct spraying. "Tedion" acts efficiently as ovicide by direct spraying and shows moreover a residual effect. However, it displays, to a lesser extent, activity against adults. "Ovotran" is slightly superior to the preceding compound in respect to activity against adults. However, it is inferior in regard to ovicidal action, and residual effect. The three new compounds, included in the class which is object of the present invention, show a more complete action spectrum against mites, since they possess the considered three characteristics to a high degree.

Persistence of activity, either against eggs or adult mites, of the new compounds was confirmed also by field tests described in Examples 22 and 23.

Furthermore, it has been found that the compounds comprised in the claimed class act according to a special mechanism which inhibits the hatching of the eggs, which the females lay after having been in contact with the active compounds or after ingesting them (or their "metabolites"), on untreated leaves (see Example 31—Table XIII and Example 32—Table XIV).

It has also been found that the compounds comprised in the general formula (1) are active against hibernant eggs.

This is an important practical characteristic, since hibernant eggs (laid between the end of summer and late autumn and hatching in spring) are notoriously much more resistant towards the action of the pesticides than the summer eggs of the mites (see Example 33—Table XV).

Finally, they have also an outstanding action against the insects as hereunder demonstrated:

Four days old newborn of *Locusta migratoria migratorides* (Orthoptera) fed with leaves of graminacea treated by spraying with solutions containing 1% (1 part per thousand) of active substances are totally destroyed within 48 hours after treatment with the products obtained in Examples 5, 7, 8, and 80% destroyed with that of Example 6.

The aphid *Acyrtosiphon onobrychis* (Emiphtera) is wholly destroyed, within 24 hours from treatment, by spraying with solutions containing 1% of active substances on broad bean seedlings, previously infested, said substances being those of Examples 5, 6, 7, 8. "Tedion" (2,4,5,4' - tetrachlorodiphenylsulfone) kills, under the same conditions, 69% thereof.

On newborn larvae (2 days old) of *Pieris brassicae* (Lepidoptera), transferred to cabbage leaves gathered one day after treatment of the plants with solutions containing 1% of active substances, the following results were obtained, after 24 and 72 hours of stay of larvae on the leaves.

Product obtained in Example	Percent mortality	
	24 hours	72 hours
5-----	88	100
7-----	100	100
8-----	100	100
Sevin ¹ -----	77	81

¹ N-methyl-1-naphthylcarbamate, usually employed against larvae of Lepidoptera.

Newborn larvae of *Carpocapsa pomonella* (Lepidoptera) transferred, 24 hours after treatment, to small apples which have been treated with solutions containing 1% of active substances, were killed to the extent of 100% with

the product obtained in Example 5, 33% with that of Example 6, 57% with that of Example 7, and 100% with that of Example 8.

Adult specimens of *Musca domestica* (Diptera), after a stay of 24 hours in Petri dishes of 85 mm. diameter treated with 100γ active substance for each dish, were totally destroyed with the products obtained in Examples 5, 6, 7, 8.

Four days old larvae of *Aedes aegypti* (Diptera, mosquito) which were left for 24 hours in a water solution containing one part per million of active substance, were 100% destroyed by the product obtained in Example 5, 33% by that of Example 6, 4% by that of Example 7, and 100% by that of Example 8.

Newborn larvae (2-3 days old) of *Chrysomela decemlineata* (Coleoptera) sprayed with solutions containing 1% of active substances were 100% destroyed by the products of Examples 5, 7, 8, and 30% with that of Example 6.

From what it is stated hereinabove, and from the supporting data presented below, it is clearly evident that the compounds comprised in the general formula of the present invention have a particularly wide spectrum of action, and they must thus be considered agents having outstanding efficiency against pests.

The compounds in accordance with the present invention may be formulated without difficulty by conventional means. The compounds of the invention may be used either as sole active ingredient or in admixture with each other or in admixture with other pesticides having a different activity.

A preferred way is to formulate the compositions as emulsifiable liquids, which are obtained by dissolving the active substances or substances in suitable solvents or mixture of solvents, together with one or more surface active substances added to make the preparation emulsifiable in water.

For special purposes, the substances of the present invention may be formulated as powders for dry dusting, by direct admixture of the active substance or substances with inert substances such as talc, pyrophyllite or china clay, or as wettable powders by direct admixture of the active substance with inert substances such as kieselguhr, clay, attapulgite, and surfactants, which make the formulated compound dispersible in water.

Toxicity data toward cold-blooded animals is presented below. The indicated values represent the L.D. (lethal dose) 50 expressed in mg./kg. of treated animal (white mouse).

	Product	Toxicity by oral administration	Toxicity by endovenous administration
55	Methylester of $\beta\beta$ -difluorethylidiphosphoryl-acetic acid	1 1,250	1 250
60	Ethylester of $\beta\beta$ -difluorethylidiphosphoryl-phenyl-acetic acid	800	1 150
65	β -Fluorethylester of diethylidithiophosphoryl-phenyl-acetic acid	20	22
	β -Fluorethylester of $\beta\beta$ -difluorethylidithiophosphoryl-phenyl acetic acid	110	56
	β -Fluorethylester of diethylidithiophosphoryl-phenyl acetic acid	20	9
	β -Fluorethylester of dimethylidithiophosphoryl-phenyl-acetic acid	40	23

¹ At these doses no mortality occurs.

The following examples are reported to illustrate the process of preparation, and also the acaricide and ovicide activity of the compounds belonging to the claimed class, as well as the formulations containing them. It is to be understood that said examples are not intended to restrict the scope of the present invention.

7
EXAMPLE 8

92.7 ml. of a water solution of the sodium salt of dimethyl-dithiophosphoric acid (titer 2.48 mol/lit.) are added to 52.8 g. bromophenyl-acetate of β -fluorethyl alcohol, diluted with 80 ml. acetone; then the mixture is stirred at room temperature (20-23° C.) for 20 hours. The organic phase is separated by decantation, and is reduced to a small volume under reduced pressure and poured into 50 ml. water. After being taken up again with 30 ml. methylene chloride, washed with water, dried on CaCl_2 and evaporated under reduced pressure, 59.7 g. of a light reddish oil are obtained, consisting of the β -fluorethylester of dimethyl-dithiophosphoryl phenylacetic acid of the formula:

which on analysis shows: P found=8.83-8.85%, P calc.=9.15%.

EXAMPLE 9

49 ml. of a water solution of sodium salt of diethyl dithiophosphoric acid (titer 3.22 mol/lit.) are added to 21 g. chloroacetate of β -fluorethyl alcohol diluted with 50 ml. acetone; the mixture is stirred at about 25° C. for 10 hours. The reaction mixture is diluted with 70 ml. water, and the organic layer is separated by decantation and reduced to small volume under reduced pressure. The residue is taken up again with 30 ml. methylene chloride, washed with water, dried on CaCl_2 and evaporated under reduced pressure. 38.5 g. of a light yellow oil are obtained as residue, consisting of the β -fluorethylester of diethyl dithiophosphoryl acetic acid of the formula:

showing, on analysis, P found=10.79-10.85%; P calc.=10.67%.

EXAMPLE 10

69 ml. of a water solution of the sodium salt of $\beta\beta$ -difluorethyl-dithiophosphoric acid (titer 1.84 mol/lit.) are added to 15.5 g. chloroacetate of β -fluorethyl alcohol diluted with 40 ml. acetone; the mixture is then stirred at room temperature for 30 hours. The organic phase is separated, evaporated under reduced pressure, and the residue poured into 35 ml. water. It is then separated, taken up again with methylene chloride and washed once more with water. After drying on CaCl_2 , and evaporating under pressure, 28 g. of light yellow oil are obtained, consisting of the β -fluorethylester of $\beta\beta$ -difluorethyl dithiophosphoryl acetic acid, having the formula:

which, on analysis, shows: P found=9.15-9.20%; P calc.=9.49%.

EXAMPLE 11

65.6 g. bromophenylacetate of 2,2-3,3-tetrafluoropropyl alcohols diluted with 30 ml. acetone are added to 44.8 g. potassium diethyl dithiophosphate in 50 ml. acetone. The reaction is exothermic. The reaction mixture is stirred at 20-25° C. for 6 hours, the refluxing of the solvent being continued for half an hour. After cooling at room temperature, the mixture is poured into 100 ml. water; the organic phase is separated and most of the acetone is evaporated under reduced pressure. The residue is taken up again with 50 ml. methylene chloride, then washed with water, then with diluted NaHCO_3 solution, and finally once more with water. After drying on CaCl_2 and evaporation under reduced pressure, 76.8 g. oil are obtained, consisting of the 2,2-3,3-tetrafluoropropylester

70

of diethyl dithiophosphoryl phenylacetic acid of the formula:

which, on analysis, shows: P found=7.02-7.06%; P calc.=7.13%.

EXAMPLE 12

94 ml. of a water solution of the sodium salt of $\beta\beta$ -difluorethyl dithiophosphoric acid (titer 1.84 mol/lit.) are added to 49.2 g. bromophenylacetate of 2,2-3,3-tetrafluoropropyl alcohol diluted with 50 ml. acetone; the mixture is stirred at a temperature in the range 20-25° C. for 9 hours. The organic phase is separated and concentrated under reduced pressure; the residue is taken up again with 30 ml. methylene chloride and washed with water, then with diluted NaCHO_3 solution and finally once more with water. After drying on CaCl_2 and evaporation under reduced pressure, a residue is obtained of 61.5 g. oily product, consisting of the 2,2-3,3-tetrafluoropropylester of $\beta\beta$ -difluorethyl dithiophosphoryl phenylacetic acid of the formula:

15 20 25

which, on analysis, shows: P found=6.43-6.44%, P calc.=6.58%.

EXAMPLE 13

25 30 35 40 45

23.8 g. bromophenyl acetate of 2,2-3,3-tetrafluoropropyl alcohol diluted with 15 ml. acetone are added to 15.6 g. sodium dimethyl-dithiophosphate dihydrate in 25 ml. acetone. A mild exothermic reaction occurs. The mixture is stirred at about 25° C. for 10 hours, and is then diluted with 30 ml. water, and the organic phase separated. The latter is concentrated under reduced pressure, and the residue is then taken up again with 20 ml. methylene chloride. After washing with water, and then with NaHCO_3 diluted solution, and finally once more with water, the residue is dried on CaCl_2 and evaporated under reduced pressure, obtaining as residue 23.5 g. oily substance, consisting of the 2,2-3,3-tetrafluoropropylester of dimethyl dithiophosphoryl phenylacetic acid of the formula:

showing, on analysis, P found=7.49-7.50%; P calc.=7.62%.

EXAMPLE 14

55 60 65

27 g. of potassium $\beta\beta$ -difluorethyl-thiophosphate and 24.3 g. of α -ethyl bromophenylacetate are mixed in 100 cc. of acetone while agitating. The mixture is heated to 40° C. for 2 hours and is kept at room temperature for 20 hours. Most of the solvent is eliminated under reduced pressure and the residue is poured into 60 cc. of H_2O . The oil thus obtained is extracted with 50 cc. of methylene chloride and is dried on CaCl_2 .

After complete elimination of the solvent under reduced pressure 29.5 g. of an oily liquid essentially consisting of the ethylene ester of $\beta\beta$ -difluorethyl thiophosphorylphenyl acetic acid, are obtained.

70 75

Analysis.—P calc.=8.41%. P found=8.03-8.09%.

EXAMPLE 15

27 g. of potassium $\beta\beta$ -difluoroethyl-thiophosphate and 14 g. of β -fluoroethylchloroacetate are mixed in 100 cc. of acetone while agitating.

By operating as described in Example 1, 21 g. of an oily liquid are obtained. This liquid is distilled under a high vacuum.

The fraction (15 g.) which is distilled between 158 and 161° C. at 0.05 mm. Hg is collected. It consists of the β -fluoroethyl ester of $\beta\beta$ -difluoroethylthiophosphoryl acetic acid.

Analysis.—P calc.=9.98%. P found=9.61-9.60%.

EXAMPLE 16

27 g. of potassium $\beta\beta$ -difluoroethyl-thiophosphate and 26 g. of β -fluoroethyl α -bromophenylacetate are mixed with 100 cc. of acetone while agitating.

By operating as indicated in Example 1, 26 g. of an oily liquid are obtained. This liquid is then purified by dissolving it in 50 cc. of CH_2Cl_2 , and then precipitating with 110 cc. of petroleum ether.

The oily fraction thus precipitated is collected and solvent traces are eliminated.

8 g. of an oily liquid prevailingly consisting of the β -fluoroethylester of $\beta\beta$ -difluoroethyl-thiophosphorylphenyl acetic acid are obtained.

Analysis.—P calc.=8.02%. P found=7.44-7.66%.

EXAMPLE 17

A spraying formulation, which may be profitably employed in the control of acarids and the eggs thereof, may be prepared by dissolving 20 parts of the β -fluoroethylester of diethyl dithiophosphoryl phenylacetic acid in 77 parts xylene, and by adding 2 parts of an anionic surfactant selected from the class of alkylarylsulphonates or alkylsulphates, and 1 part of a non-ionic surfactant selected from the class of ethylene oxide condensation products with fatty acids or with fatty alcohols or alkyl-phenols.

EXAMPLE 18

A spraying formulation, which may be employed against acarids and the eggs thereof, is prepared by dissolving 20 parts of β -fluoro-ethylester of $\beta\beta$ -difluoroethyl dithiophosphoryl acetic acid in 75 parts xylene and adding 2.5 parts of an anionic surfactant selected from the class of alkylarylsulphonates or alkylsulphates and 2.5 parts of a non-ionic surfactant selected from the class of ethylene oxide condensation products with fatty acids, or alcohols, or with alkyl-phenols.

EXAMPLE 19

A spraying formulation, which may be employed in the control of acarids and their eggs is prepared by dissolving 10 parts of β -fluoro-ethylester of dimethyldithiophosphoryl phenylacetic acid and 20 parts of α -cyanisopropylamide of O,O-diethyl diphosphoryl acetic acid in 67 parts xylene, while adding 2 parts of an anionic surfactant selected from the class consisting of alkylarylsulphonates or alkylsulphates, and 1 part of a non-ionic surfactant selected from the class consisting of the ethylene oxide condensation products with fatty acids or alcohols or with alkylphenols.

10
EXAMPLE 20

A wettable powder may be suitably prepared by mixing 3-5% of a compound belonging to the claimed class together with 97-95% talc.

5
EXAMPLE 21

A wettable powder may be suitably prepared by mixing 20% of a compound belonging to the claimed class together with 75% diatomaceous earth and 5% of an anionic surfactant, selected from the class consisting of alkylarylsulphonates or alkylsulphates.

In the following example, are reported data relating to the activity, against mite adults and mite eggs, of a number of the prepared compounds. The determinations were carried out according to the hereinafter indicated procedure on the following test mites:

- (1) *Metatetranychus ulmi*, susceptible strain (S) and strain (R) resistant to the action of other acaricides;

- (2) *Tetranychus telarius*.

All the tests on *Tetranychus telarius* were carried out on bean plants in pot. With *Metatetranychus ulmi*, strain (S) and (R), the tests were partially performed on pot bred apple trees, partially on field bred apply plants. The following technique was employed for carrying out the tests:

(1) *Tests on pot plants*.—Discs having a diameter of 2.8 cm. are recovered from apple or bean leaves and sprayed with the products under tests before or after having been infested with the adults.

(2) *Tests on field plants*.—Apple plants are sprayed with the products at 0.02% of active substance, before or after infecting them with mites; some leaves are then sampled at successive time intervals, while obtaining therefrom discs of 2.8 cm. diameter.

35
EXAMPLE 22

Activity against adults is determined by direct spraying at *Metatetranychus ulmi* S, on discs of apple tree leaves, in the laboratory.

40 Discs are infested, on the upper leaf face, each with 60 adult females, then sprayed with the products to be tested and kept for 48 hours in open Petri dishes as 24°-26° C.

Percentage mortalities, determined with a stereomicroscope, are reported in Table I.

45

Persistance of activity is determined against eggs of *Metatetranychus ulmi* S, laid by untreated females on apple tree leaves treated on the field (date of treatment of plants: May 9, 1961).

Plants are sprayed with the products at 0.02% of active substance, then 1, 3, 6, 13 and 18 days after the day of treatment 8 leaves are gathered from each plant. From the leaves are obtained the discs, which are infested partly on the upper side and partly on the underlying side of the leaf, each with 100 adult females. After 24 hours the mites are removed, and the discs together with eggs are kept inside of open Petri dishes, for a few days beyond the hatching date of untreated eggs. The results are reported in Table IV.

EXAMPLE 27

Persistence of activity against adults of *Metatetranychus ulmi* S, on apple tree plants on the field.

Persistence of activity against adults is determined by measuring percentage mortality, at different time intervals after treatment (1, 3, 6 and 13 days), of the adults removed after 24 hours of contact with the surface of treated leaves, according to Example 22.

The results are reported in Table VI.

Table VI

EXAMPLE 29

Activity against adults is determined by residual effect a short time (24 hours) after treatment, on *Metatetranychus ulmi* susceptible strain S and resistant strain R.

The test was carried out in the field by spraying (on July 25, 1961) young apple trees with the products under examination at a concentration 0.02% of active substance. 24 hours after treatment 5 leaves per plant are gathered; from said leaves the discs are obtained whereupon adult mites belonging to the two above-mentioned strains are allowed to rest for 24 hours. The results are reported in Table VIII.

Table VIII

Products obtained in Example	Contact leaf surface*	Percentage dead mites	
		Susceptible S	Resistant R
5-----	I-----	98	90
5-----	U-----	99	84
6-----	I-----	79	90
6-----	U-----	12	66
7-----	I-----	98	77
7-----	U-----	95	100
8-----	I-----	3	30
8-----	U-----		29

*I=under side leaf; U=upper side leaf.

ulmi S is determined by direct spraying on apple tree plants, on the field. The plants are infested with mites in the field and after about one month are sprayed with the products under examination, at 0.02% concentration of active substance.

24 hours after treatment 5 leaves per plant are gathered; the discs obtained from the leaves are kept at 24°-26° C. inside open Petri dishes for several days beyond the hatching date of unsprayed eggs; then the percentages of unhatched eggs are determined, which are reported

70

75 IX.

In the same table the activity values against adults are reported, obtained by determining the number of females present on the leaves before the spraying and at different time intervals after the spraying.

EXAMPLE 30

Persistence of activity is determined against eggs of *Metatetranychus ulmi* susceptible strain S and resistant strain R, said eggs being laid by untreated females on leaves of apple trees sprayed on the field.

Plants are sprayed with the products at a concentration 0.02% of active substance, and then, 1, 3, 6, 14 and 20 days after the treatment date, 8 leaves are gathered from each plant. From the leaves discs are obtained which are infested with about 100 adult females. After 24 hours, the acarids are removed and the discs together with the eggs are kept at 24°-26° C. inside of open Petri dishes for a number of days beyond the hatching date of untreated testimony eggs. The results are reported in Table IX.

Table IX

Product obtained in Example	Side of egg deposition on leaf surface ¹	Percentage of unhatched eggs ²									
		1 day		3 days		6 days		14 days		20 days

55 35 Ovicidal activity displayed by the active substances when sprayed on females of *Metatetranychus ulmi* on discs of apple tree leaves.

60 60 Discs obtained from apple tree leaves, infested with females of *Metatetranychus ulmi*, are treated with the substances under test. After two hours the females are transferred to discs of untreated leaves and kept on wetted cotton in Petri dishes. The females are allowed to lay eggs for 24 hours, when they are eliminated. The percentage of unhatched eggs is then calculated. The results obtained are reported in Table XIII.

Table XIII

Product obtained in Example	Percentage of unhatched eggs		
	0.01% _{oo}	0.1% _{oo}	1% _{oo}
5	21	97	100
6	51	98	100
7	76	94	100
8	76	100	100

17
EXAMPLE 35

Ovicidal activity is determined by the effect of the active substances on females feeding upon the product absorbed by leaves. The substances under test, diluted in water, are distributed dropwise, by means of a micro-syringe, on the upper face of leaves of bean and apple plants bred in pots. After a pre-established time interval the females of *T. telarius* and *M. ulmi* are transferred onto the underlying, untreated face of the same leaves and the mites are kept confined thereon by means of lanolin. They are allowed to feed and lay eggs for 24 hours, and the females are then eliminated. The percentage of unhatched eggs, laid on the underlying, untreated, face of the leaves is calculated. The results are reported in Table XIV.

Table XIV

	Product obtained in Example	Percentage of unhatched eggs laid on the untreated face of the same treated leaves
<i>Metatetranychus ulmi</i> -----	5	72
	6	21
	7	74
	8	54
<i>Tetranychus telarius</i> -----	5	55
	6	68
	7	59
	8	77

EXAMPLE 36

Effect of the hereinafter mentioned products on hibernant eggs of *Metatetranychus ulmi*.

Date of the treatment: March 26, 1962.

Beginning of the hatching of the eggs: about April 15. The results are reported in Table XV.

Table XV

Product obtained in Example	Active subst. concentration %	Total number of eggs	Number of unhatched eggs	Percent unhatched eggs

The term lower alkyl means alkyl radicals having up to six carbon atoms.

We claim:

1. A phosphoric acid ester of the formula:

in which R, R₁, and R₂ are taken from the group consisting of lower alkyl, lower alkenyl, lower alkynyl, fluoro-lower alkyl, fluoro-lower alkenyl, and fluoro-lower alkynyl; at least one of the R, R₁, and R₂ radicals being one of said fluoro radicals; R₃ being taken from the class consisting of hydrogen and phenyl; X being taken from the class consisting of sulfur and oxygen.

2. A phosphoric acid ester of the formula:

wherein R, R₁ and R₂ are taken from the radicals consisting of lower alkyl, lower alkenyl, lower alkynyl, fluoro-lower alkyl, fluoro-lower alkenyl and fluoro-lower alkynyl; at least one of R, R₁ and R₂ being one of fluoro radicals, and X is taken from the group consisting of sulfur and oxygen.

3. Methyl ester of $\beta\beta$ -difluoroethyl dithiophosphorylactic acid.

4. β - Fluoroethylester of diethyl dithiophosphoryl phenylacetic acid.

5. β -Fluoroethylester of $\beta\beta$ -difluoroethyl dithiophosphoryl phenylacetic acid.

6. β -Fluoroethylester of diethyl mono-thiophosphoryl phenylacetic acid.

7. β -Fluoroethylester of dimethyl dithiophosphoryl phenylacetic acid.

8. β -Fluoroethylester of $\beta\beta$ -difluoroethyl dithiophosphoryl acetic acid.

9. Ethylester of $\beta\beta$ - difluoroethyldithiophosphoryl phenylacetic acid.
